LADY'S HAIR ORNAMENT

Siegfried Behr, Flushing, N. Y.

Application October 25, 1956, Serial No. 43,519

Term of patent 3½ years

(Cl. D86—10)

Fig. 1

Fig. 3

Fig. 1 is a plan view of a lady's hair ornament showing my new design.

Fig. 2 is an edge view thereof.

Fig. 3 is a detail view of one of the settings.

I claim:

The ornamental design for a lady's hair ornament, as shown.
